Primary Examiner — Katherine Glennon

(57) **CLAIM**

The ornamental design for a clock face as shown and described.

DESCRIPTION

FIG. 1 is a front view of a first embodiment of a clock face, showing my new design;

FIG. 2 is a front view of a second embodiment thereof; and,

FIG. 3 is a front view of a third embodiment thereof.

The solid black area shown in the drawings represents a contrast in appearance and is not intended to indicate any specific color, or material.

1 Claim, 3 Drawing Sheets

FIG. 1

FIG. 2

FIG. 3
